CHAIR OR THE LIKE

Herbert Ritts, 2221 S. Sepulveda Blvd.,
Los Angeles, Calif.

Filed July 25, 1963, Ser. No. 75,974

Term of patent 7 years

(Cl. D15—1)

I claim:

The ornamental design for a chair or the like, substantially as shown.
